ORRIN UPDIKE, OF GRASS LAKE, MICHIGAN.

Letters Patent No. 102,887, dated May 10, 1870.

IMPROVEMENT IN METALLIC CHURN-DASHER.

The Schedule referred to in these Letters Patent and making part of the same.

To whom it may concern:

Be it known that I, ORRIN UPDIKE, of Grass Lake, in the county of Jackson and State of Michigan, have invented a new and useful Improvement in Metallic Churn-Dashers; and I do declare that the following is a true and accurate description thereof, reference being had to the accompanying drawings and to the letters of reference marked thereon, and being a part of this specification, in which—

Figure 1 is a perspective, and

Figure 2 a bottom plan of my device.

Like letters refer to like parts in each figure.

The nature of this invention relates to the construction of a churn-dasher, and consists in the peculiar construction of the same, being a disk composed of a series of rings included within each other at regular intervals, the center one having wings upon its periphery, and united by radial bars upon the same plane, surmounted with flanges radiating from a hollow socket in the center of said disk, the whole being cast in one piece of suitable metal.

In the accompanying drawings—

A represents a series of rings, each being larger

than the one nearer the center, laid upon the same plane, and joined together by a series of radial bars, B, with the outside ring, provided with rings C projecting on the same plane.

D is a socket, designed to receive the lower end of a suitable handle, which is secured by a screw through the hole E in the bottom of the socket.

Radiating from the socket, and at right angles with each other, are the wings or flanges F, the whole being cast in one piece. If cast in iron or any metal that will corrode, they should be galvanized or otherwise coated with any non-corroding substance.

What I claim as my invention, and desire to secure by Letters Patent, is—

The metallic churn-dasher above described, composed of the rings A, the bars B, the wings C, the socket D, with an opening, E, and the flanges F, cast in one piece of suitable metal, constructed and arranged as described and for the purpose set forth.

ORRIN UPDIKE.
